UNITED STATES PATENT OFFICE.

AUGUSTE SCHEUCHZER, OF RENENS, NEAR LAUSANNE, SWITZERLAND, ASSIGNOR TO FERRODESHEREUSE SCHEUCHZER SOCIETE ANONYME, OF RENENS, SWITZERLAND.

RAILROAD-TRACK-WEEDING MACHINE.

Application filed July 31, 1923. Serial No. 654,939.

To all whom it may concern:

Be it known that I, AUGUSTE SCHEUCHZER, citizen of Switzerland, residing at Renens, near Lausanne, Switzerland, have invented 5 certain new and useful Improvements in Railroad-Track-Weeding Machines, of which the following is a specification.

This invention relates to machines for removing weeds from railway tracks of the 10 type in a which a tool blade is carried by a truck running along the rails and projecting therefrom into the road between the individual rail tracks or the road on the outside edge of the rail track so as to remove the 15 weeds by a hoeing action.

In the improved apparatus constructed in accordance with this invention, the tool is carried by an arm which is capable of movement about a vertical axis so that the tool 20 can move clear of obstructions which it may encounter.

In the accompanying drawings which represent one embodiment of the present invention and in which only sufficient detail 25 is shown to enable the invention to be understood,

Fig. 1 represents an end elevation of the apparatus.

Fig. 2 is a front elevation of the part 30 shown in Fig. 1, and

Fig. 3 is a plan view to enlarged scale showing the tool in its operative and inoperative positions.

A slide *a* formed of channel sections back 35 to back is transversely adjustable between rollers *b*¹, *b*² carried by the frame of the truck. The slide is transversely adjusted by means of a hand lever *f* carried on the platform *d* of the truck and provided with suitable stop 40 notches. This hand lever is connected by a link *e*² to an arm *e* pivoted about a pin *c* on the platform the arm *e* being connected to the slide *a* by a link *e*¹. The end of the slide *a* carries a vertical bearing in which a spindle 45 *g* is axially and pivotally movable. The axial movement is effected by means of a cable *h* carried by a hoisting pillar *i*. The lower end of the spindle *g* has pivoted to it

an arm *g*¹ through which passes the vertical spindle of the tool blade *k*. The upper end 50 of this spindle carries a forked lever *k*¹ to which is attached a cable *k*² which passes round a pulley *k*³ housed in the arm *g*². The end of this cable *k*² is connected to a spring *k*⁴ which is strong enough to provide 55 the necessary resistance to traction of the tool through the bed but which will yield when any movable obstacle is encountered and will thus enable the parts to swing over to the position shown in dotted 60 lines in Fig. 3. The arm *g*¹ is supported by a cable *l* which is connected to the crank arm *g*⁵ of a crank lever *g*³ pivoted upon a collar *g*⁴ carried by the spindle *g*, the crank 65 lever *g*³ can be adjusted to vary the angle of the tool blade to the horizontal.

I claim:

1. In a railroad-track weeding machine and in combination a truck, a transverse slide provided thereon and extending sideways to the outside of the truck, a vertical spindle mounted rotatably at the end of said slide, an arm hinged to the lower end of this spindle, a crank-lever carrying a tool blade and adapted to swing in a horizontal plane 70 at the end of this arm and means for exerting a resilient forward pull on said crank lever, so as to cause the blade to attack the ballast substantially as shown and described.

2. In a railroad-track weeding machine 80 and in combination a truck, a transverse slide provided thereon and extending sideways to the outside of the truck, a vertical spindle mounted rotatably and slidably in an axial sense at the end of said slide, an arm 85 hinged to the lower end of said spindle and carrying the tool blade at its free end, means for lifting this arm to a certain amount by hand, a hoisting pillar arranged on said slide, and means for hoisting said spindle on 90 said pillar, so as to bring said tool into a position of rest, all for the purpose set forth and substantially as shown and described.

In testimony whereof I affix my signature.

AUGUSTE SCHEUCHZER.
